BALLET SLIPPER AND METHOD OF MAKING THE SAME

Application filed July 26, 1930. Serial No. 470,839.

This invention relates to ballet slippers, and method of making the same, with particular reference to slippers having elastic means in the upper portion so that the slippers will at all times snugly fit the feet of the wearer. 5

It is a recognized fact that in the act of toe dancing the feet of the dancer frequently arch when on the toes. Such arching 10 shortens the distance between the toes and the heels with the result that if the ballet slipper fits the foot snugly when the ball of the foot is on the floor, then when the dancer is on her toes the heel portion of the slipper 15 bulges from the heel of the foot leaving a gap, presenting an unsightly appearance, and sometimes a portion of the heel of the slipper sags.

The slipper of the present invention overcomes the above recited objections in that it 20 provides an elastic portion at the heel to compensate for variations in the length of the feet of the wearer when flat on the floor or on the toes during the toe dancing act whereby the slipper fits snugly at all times without gapping and without losing its shape. 25

An object of the present invention is to provide a ballet slipper with means for causing the slipper to fit the wearer's foot snugly 30 in all positions of use.

Another object of the invention is to provide a method of making a ballet slipper so that the resulting slipper will snugly fit the wearer's foot at all times.

35 A still further object of the invention is to provide a ballet slipper with elastic inserts at the heels to compensate for variations in the movements and shape of the foot of the wearer in toe dancing.

40 A still further object of the invention is to improve ballet slippers so that the same will snugly fit the feet of the wearer at all times and at the same time provide comfort in all positions.

45 The slipper includes an elastic portion adjacent the heel of the slipper which allows the movements of the material of the upper as the foot of the wearer changes its shape and position in the act of toe dancing. The 50 method includes the insertion of an elastic

material between spaced ends of an upper, the disposition of a lining material underlying the elastic material so that the upper may be stretched on a last and then after the upper has been lasted such portion of the 55 lining underlying the elastic portion is cut away to allow movement of the upper.

An embodiment of the invention is illustrated in the accompanying drawings and the views thereof are as follows:

50 Figure 1 is a side elevational view of a slipper embodying the present invention showing the same on the foot of a dancer with the same in toe dancing position.

Figure 2 is a side elevational view of a slipper embodying the present invention shown on the foot of a wearer with the foot flatwise on the floor.

55 Figure 3 is an elevational view of the rear end of the slipper.

Figure 4 is an enlarged sectional view taken in the plane of line IV—IV of Figure 3.

The drawings will now be explained.

The form of slipper chosen to exemplify the present invention is illustrated as comprising 75 a sole 1, a toe portion 2, and a heel portion 3. The toe and heel portions 2 and 3 constitute the upper and are made in the usual manner except as to the heel construction.

80 The ends 4 and 5 of the upper material adjacent the heel are cut away to provide a space. Figure 3 illustrates the space so formed as extending each side from the middle line of the back stay 6. The back stay in this instance consists of a narrow strip of 85 which the upper is made, preferably satin, which at its upper end is secured to a finishing strip 7 sewed along the upper margin of the upper. The lower end of the back stay 6 is attached to the sole 1 in the same manner 90 as the balance of the upper is attached to the sole or last.

95 A piece of elastic material has its central portion stitched to the back stay 6 and its margins to the adjacent margins of the ends 95 of the upper of the heel, providing the elastic gores 8 and 9 between the back stay 6 and the adjacent spaced ends of the upper. The elastic material just described may be inserted in two pieces or as a unitary piece, as de- 100

scribed the margins of the two pieces would be stitched to the margins 4 and 5 of the upper and to the margins of the back stay 6. Figure 4 illustrates a single piece of elastic material stitched in the manner just described.

6 The upper is constructed usually of an outer layer of finished material 10 and a lining 11 stitched together at the top margins thereof and covered by the binding strip 7.

10 The lining material is applied to the upper of the present invention underlying the elastic material making the lining continuous throughout the interior of the outer layer 10 in the usual manner. This is for the purpose 15 of stretching the upper on the last as considerable force is necessary to properly fit the upper for attachment to the last and often times the operator uses pliers or similar tools for stretching the upper on the last. The 20 arrangement of the lining underlying the elastic material therefor prevents the elastic material from stretching during the lasting operation. As soon as the upper has been 25 properly lasted and removed therefrom portions of the lining material underlying the elastic material is cut away allowing the elastic material to function when the slipper is applied to the foot of the dancer.

30 The upper is illustrated as comprising two parts, a toe portion 2 and the heel portion 3 as before stated which portions are stitched together along seam 12.

35 The utilization of the back stay 6 maintains the heel portion of the slipper in proper form so that there is no sagging of the heel portion of the slipper when the dancer is on her toes as illustrated in Figure 1. The back stay 6 also adds to the appearance of the slipper and at a distance it is impossible to 40 discern the utilization of the elastic inserts or gores 8 and 9.

45 A ballet slipper must snugly fit the foot of the wearer. Should the slipper be fitted snugly to the foot with the foot on the floor as shown in Figure 2, then when the dancer is on her toes the foot curves thus shortening the distance between the toes and the heel of the same decreasing the space occupied at the heel of the slipper. Ordinarily such shortening of the foot causes the heel of the slipper to sag or to lie away from the heel of the dancer making the slipper uncomfortable and unsightly.

50 The slipper embodying the present invention may be fitted to the foot of a dancer as shown in Figure 2, in which event the elastic gores 8 and 9 or a single gore, of one, instead of two, be used, causes snug fit of the shoe or slipper and at the same time allowing a comfortable fit, and when the dancer is on her toes in the position of Figure 1, the elastic will then contract causing snug fit of the heel of the slipper to the foot of the dancer and preventing any spacing between the heel of the slipper and the foot and

5 preventing any sagging of the heel of the slipper.

6 If the foot is placed flatwise on the floor it necessarily spreads to some extent, consequently a ballet slipper fitted to a foot in this 70 position will be too large when the dancer is on her toes as the foot necessarily becomes shortened as above described. Furthermore, during toe dancing the foot contracts sideways so that a slipper which is comfortable 75 when the foot is flatwise on the floor would be too large and would lie away from the foot or sag. The slipper of the present invention prevents all of these disadvantages and overcomes these objections in that it 80 causes the slipper to fit the foot snugly in all positions of toe dancing as well as when the dancer is walking with her feet on the floor. The elastic is of such size and resiliency as to allow a spread of the slipper when 85 the dancer is walking with her soles on the floor and in a position to contract the slipper when the dancer is on her toes.

90 Figure 4 illustrates an arrangement of the illustrated embodiment of the invention with the ends of the lining turned back and stitched to the back stay 6 and the white spaces indicates the portion of the lining cut out after the upper has been lasted. Spaces between the inturned ends of the lining 95 11 and the lining 11 proper allow full resilient action of the elastic material or gore after the shoe has been completed.

100 The gist of the invention resides in the provision of an elastic insert or gore in a ballet slipper to allow the slipper to conform to spreading and contracting of the feet of the dancer in the various positions assumed in the act of toe dancing. The method involves the manner of inserting resilient or 105 elastic material in a ballet slipper and the provision of a lining which prevents stretch of the elastic material while the upper is being lasted and then with the lining cut away underlaying the elastic material in the slipper. 110

115 The invention has been described herein more or less precisely as to details yet it is to be understood that changes may be made in the arrangement and proportion of parts and that equivalents may be substituted without departing from the spirit and scope of the invention.

120 The invention is claimed as follows:

1. A method of making ballet slippers which consist in inserting elastic material in a slipper connected to spaced portions of the slipper, inserting an upper lining with the same underlying the elastic material, then applying the upper to a last and utilizing the unbroken lining for allowing stretching of the upper to the last, and then after the upper has been lasted removing such portions of the lining as underlie the elastic material. 125

130 2. The method of making a ballet slipper

which consists in spacing the ends of the upper adjacent the heel, inserting elastic material between the spaced ends of the upper, and applying an inner lining underlying the elastic material for preventing stretch of the elastic material during lasting.

3. The method of making a ballet slipper which includes the formation of an upper with the ends of the upper adjacent the ends of the heels in spaced relation, inserting an elastic material between the spaced ends of the upper, then applying an inner lining to the upper extending underneath the elastic material, then applying the upper to a last utilizing the lining for preventing stretch of the elastic material while lasting said upper, and then cutting away the lining underneath the elastic material.

4. The method of making ballet slippers which consists in forming the upper with portions thereof in spaced relation, inserting elastic material to bridge said space, then applying an inner lining underneath the elastic material, then lasting the upper and utilizing the lining for preventing stretch of the elastic material while lasting the upper, and then removing the lining underlying the elastic material.

5. A ballet slipper including an upper having an unbroken top margin, the adjacent rear ends of the rear portions of the upper being joined together at the top margin and spaced from each other below said top margin, the spaced ends extending to the slipper sole, and elastic material connecting said spaced rear ends and filling the space between the same and the top margin and sole.

In testimony whereof I have hereunto subscribed my name at Chicago, Cook County, Illinois.

LEO HARRIS.
